UNITED STATES PATENT OFFICE.

FRED S. ENGLISH, OF NEW LONDON, CONNECTICUT.

SLIDER CONTROLLER FOR PRESSES.

Application filed July 6, 1922. Serial No. 573,220.

To all whom it may concern:

Be it known that I, FRED S. ENGLISH, a citizen of the United States, and a resident of New London, in the county of New London and State of Connecticut, have invented 5 certain new and useful Improvements in Slider Controllers for Presses, of which the following is a specification.

My invention relates to devices for controlling sliders for presses. In printing presses and cutting and scoring presses of the reciprocating or flat bed type, the roller bearings on which the reciprocating bed travels are usually mounted on members 10 called sliders which are themselves adapted to move back and forth over the bed tracks. Where these sliders travel just one-half as far in each direction as the bed the rollers will have a rolling contact on the tracks as 15 well as on the bed and friction is reduced to a minimum.

Where the sliders are moved by the bed only they slip more or less, especially when the bed reverses, so that the sliders get out 20 of their proper positions relatively to the bed partly due to the momentum of the sliders and partly to other causes. This causes the sliders to bump at the end of their strokes or at the time they reverse. In 25 some cases devices have been provided to cushion the sliders at the ends of their strokes and in some cases mechanism in the form of gears has been used to drive the sliders back and forth the desired distance.

One of the defects in former devices of the first type has been that springs of very limited length have been used as a matter 30 of necessity and they wear out quickly, aside from other disadvantages. In the second mentioned type of controller the sliders were always reversed at the same points and as a result depressions were made in the tracks at the points of reversal, this being called "guttering." These depressions had 35 to be eliminated after a time by regrinding the whole tracks which is a difficult thing, especially in the places where the presses are used.

The object of the present invention is to 40 overcome the objections to both the above types and to retain the advantages of both. The present device permits the sliders to change their position occasionally sufficiently 45 to eliminate the grooving or guttering action on the tracks and at the same time it tends to correct or restore the sliders to their

intended positions if they are displaced to an undesirable extent. In the present device it is feasible to use very much longer springs so that they are more durable. The device 60 also holds the sliders against lateral displacement. Other advantages will be apparent from the following detailed description.

In the drawings forming part of this 65 application,

Figure 1 is a side view of a portion of a flat bed press showing one of my improved slider controllers,

Figure 2 is a plan view thereof,

Figure 3 is a sectional view of a portion 70 of the track and bed as well as one of the sliders,

Figure 4 is a cross sectional view thereof,

Figure 5 is a side elevation of a modified 75 form of the invention, and

Figure 6 is a side elevation of still another form of the invention.

Referring first to the construction shown in Figures 1 to 3 I have shown the slider 80 at one side only of the press but it will be apparent that the device is duplicated at the opposite side of the press. I have shown part of one of the side frames 34 of a flat bed press, an impression cylinder 35 and 85 the reciprocating bed 11, the remaining parts being omitted to simplify the drawings, since they are not necessary to an understanding of my invention.

The track 12 is usually lined with a strip 90 14 of hard metal to take the wear and the bed 11 generally has a lining strip 14^a of hard metal to take the wear, and the sliders are disposed between these wear strips. I have shown the slides as composed of a bar 95 15 in which the arbors 15^a of a plurality of rollers 13 are mounted so that these rollers lie parallel to the track. The bed rests on the tops of these rollers 13 and the rollers in turn have their bearing on the track 12 so that a roller bearing is provided on which 100 the bed may reciprocate almost without friction. The greatest efficiency is attained; that is, the device operates with minimum friction, when the slider travels back and forth one half the distance traveled by the bed, this representing the rectilinear movement of the axes of the rollers 13.

Bolted to the slide bar 15 near each end 105 thereof are the castings 16 and 17, and there is a rod 18 having its ends securely fixed in these castings so that the rod 18 extends 110

parallel with the slider and the tracks or parallel to the direction of motion of the bed. This rod, therefore, reciprocates with the slider in the direction of its length. In 5 this form of my invention there is a casting 19 firmly secured to the track 12 at a point in the middle of the run of the slider and it has an aperture through which the rod 18 passes and in which aperture the rod may slide 10 freely. Around this rod 18 there is a coiled spring 20 near one end of the rod and there is a similar spring 21 surrounding the rod near its opposite end. There is a collar 22 against which one end (left end in Figures 15 and 2) of the spring 20 abuts and there is a similar collar 23 fixed to the rod 18 against which one end (the right hand end in Figures 1 and 2) of the spring 21 abuts. These collars are secured to the rod 18 pref- 20 erably by set screws 18^a to permit of their adjustment in position upon the rod. The washer 24, preferably a combination of leather and metal, is attached to or placed against one end of the spring 20 and is slid- 25 able along the rod 18; and a similar washer 25 is attached to or placed against the end of the spring 21 and is likewise slidable along the rod 18.

Operation: When the bed moves toward 30 the left there would be a tendency for the slider to continue after the bed stops, due to its momentum, and the present device may be adjusted to permit this to some degree, but before the slider reaches its extreme left 35 position in Figure 1 the washer 25 strikes the casting 19 and from then on the spring 21 is compressed between the washer 25 and the collar 23 and this spring finally arrests the movement of the slider. When the slider 40 moves to the right the compression of the spring 21 is released. Near the extreme end of the movement to the right the washer 24 comes up against the member 19 and the spring 20 is compressed until it finally ar- 45 rests the slider in this direction. The slider is not arrested exactly in the same point at each stroke in either direction, so there is no local wearing or guttering of the tracks.

When the bed reverses and commences to 50 move either to the right or to the left either the spring 20 or the spring 21 is under compression between the member 19 and the collar 24 or the collar 25. As the bed reverses the slider has a tendency to lag behind mo- 55 mentarily due to its inertia and in such case the compression spring 20 or 21, as the case may be, provides a force tending to overcome this inertia and to either start the slider with the bed or to cause it to make up 60 for any loss in motion by advancing it along the track. Thus, while the slider is not necessarily fixed in relation to the bed at all times there is a tendency to correct any momentary difference in their relationship.

65 It will be apparent that the springs 20,

21 may be made long enough to make them durable and smooth in their operation without extending the length of the tracks. It will also be apparent that the rod 18 and member 19 serve to hold the slider against 70 lateral displacement without other means.

In the form shown in Figure 5 the bearings 26 and 27 are fixed to the track 12 and the rod 28 is fixed in these bearings and consequently it does not move. A block 29 is 75 fixed to the slider and as it reciprocates it brings up first against the movable washer 24 to compress the spring 20 against the bearing member 31 and on the reverse motion it brings up against the movable washer 80 25 to compress the spring 21 against the bearing member 30. The springs perform the same function as in the first form of the invention.

In Figure 6 the bearing members 30, 31 are fixed to the slider the same as in Figure 1, and the rod, 32 fixed to these, travels with the slider. The member 33 instead of being attached to the track is, in this case, attached to the bed 11 of the press. As the bed moves twice as far in each direction as the slider the member 33 alternately compresses the springs 20 and 21 against the bearing members 31, 30 respectively. These springs, therefore, perform functions corresponding 95 to the springs 20, 21 in Figure 1.

The present device is not likely to be damaged if a tool is accidentally dropped in making adjustments on the press.

From the above it will be apparent that 100 I secure all the advantages of former devices and at the same time eliminate their objectionable features.

Having described my invention, what I 105 claim is:

1. In a press the combination with a track and a bed reciprocating on said track, a reciprocating slider having revolving bearing members on which said bed travels and means for cushioning said slider comprising 110 a spring arranged parallel and to one side of said slider and relatively movable members acting on said spring to cushion the action of said slider.

2. In a press the combination with a track and a bed reciprocating on said track, a reciprocating slider having revolving bearing members on which said bed travels and means for cushioning said slider comprising 115 a spring arranged adjacent and alongside said slider, and relatively movable members acting on said spring to cushion the action of said slider.

3. In a press the combination with a track and a bed reciprocating on said track, a reciprocating slider having revolving bearing members on which said bed travels, and means for cushioning said slider, comprising 120 springs arranged parallel and to one side of said slider and relatively movable members 125 130

acting on one of said springs to cushion the action of said slider when moving in one direction and acting on another of said springs to cushion the action of said slider 5 when moving in the opposite direction.

4. In a press the combination with a track and a bed reciprocating on said track and a reciprocating slider having revolving bearing members on which said bed travels, and 10 means for cushioning said slider, comprising a rod, a spring guided on said rod and relatively movable means for compressing said spring to cushion the action of said slider.

5. In a press the combination with a track and a bed reciprocating on said track and reciprocating slider having revolving bearing members on which said bed travels, and means for cushioning said slider, comprising 20 a rod arranged parallel and to one side of said slider, a spring guided on said rod, and relatively movable means for compressing said spring to cushion the action of said slider.

6. In a press the combination with a track and a bed reciprocating thereon, a reciprocating slider having revolving bearing members on which said bed travels, and means for cushioning said slider, comprising a rod, 30 springs guided thereon and relatively movable members for compressing one of said springs when said slider moves in one direction and for compressing another of said springs when said slider moves in the opposite direction.

7. In a press the combination with a track and a bed reciprocating thereon, a recipro-

cating slider having revolving bearing members on which said bed travels, and means for cushioning said slider, comprising a rod 40 arranged parallel and to one side of said slider, springs guided on said rod and relatively movable members for compressing one of said springs when said slider moves in one direction and for compressing another 45 of said springs when said slider moves in the opposite direction.

8. In a press the combination with a track and a bed reciprocating on said track, a reciprocating slider having revolving bearing members on which said bed travels, and means for cushioning said slider, comprising a rod, a spring guided on said rod, a collar 50 adjustable along said rod against which one end of the spring abuts and a relatively movable member for compressing said spring to cushion said slider.

9. In a press the combination of a track, a bed reciprocating on said track, a reciprocating slider having revolving bearing members on which said bed travels, and means for cushioning said slider, comprising a rod 60 secured to and lying parallel to said slider, springs arranged on said rod and movable therewith and a stationary member against which said springs alternately abut when said slider moves back and forth, whereby said springs cushion said slider near the ends of its strokes.

Signed at New London, county of New 70 London, and State of Connecticut, this 27th day of June, 1922.

FRED S. ENGLISH.
